The ornamental design for a vision module for industrial robot, as shown and described.

DESCRIPTION

FIG. 1 is a front perspective view of the vision module for industrial robot showing our new design;

FIG. 2 is a front elevational view of the vision module for industrial robot of;

FIG. 3 is a rear elevational view of the vision module for industrial robot;

FIG. 4 is a right side elevational view of the vision module for industrial robot;

FIG. 5 is a left side elevational view of the vision module for industrial robot;

FIG. 6 is a top plan view of the vision module for industrial robot; and,

FIG. 7 is a bottom plan view of the vision module for industrial robot.

The broken line portions in the drawings are shown to illustrate environment only and form no part of the claimed design.
